UNITED STATES PATENT OFFICE

2,574,467

CHRONOSCOPE

Walton W. Cushman, Webb City, Mo.

Application September 27, 1946, Serial No. 699,651

14 Claims. (Cl. 161—15)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to a chronoscope, and more particularly, to a chronoscope which is electrically operated and is especially designed to measure fractional seconds of time.

It is a major object of this invention to provide an improved chronoscope which is electrically operated and which accurately measures with a minimum margin of error periods of time less than that of a second and which chronoscope is especially adapted to measure the time required for a person to perform an act such as applying an automobile brake after a signal has been given.

It is another object of this invention to provide a device for measuring short periods of time and having a dial and pointer, each rotatable in opposite directions in a step-by-step manner in synchronism with the electrical impulses of an alternating current source.

It is a further object of this invention to provide an improved chronoscope having a dial and a pointer each rotatable alternately in opposite directions and each having separate coaxial ratchet wheels alternately driven by pawl mechanism mounted on an armature of an electromagnet.

It is still a further object of this invention to provide an improved device for measuring fractional seconds of time and having a dial and pointer alternately rotatable in opposite directions in synchronism with an alternating current source and in which the drive means includes an oscillating armature mounted on a leaf spring having one end fixed and the other end free.

Still another object of this invention is to provide an improved chronoscope having a dial mounted on a hollow shaft and a pointer mounted on a solid shaft extending coaxially through the hollow shaft, in which the shafts are provided with ratchet wheels which are alternately driven step-by-step in opposite directions, and in which means are provided for manually returning the dial and pointer to zero setting.

Still a further object of this invention is to provide a reaction time indicator including an alternating current circuit which may be closed and opened by switch means to fix the reaction time and in which electromagnetic means are included to convert the electrical impulses to mechanical impulses during the reaction time,

2

which mechanical impulses are registered on a dial.

Other objects and advantages of this invention will appear in the following detailed description and particularly will be pointed out in the appended claims, reference being had to the accompanying drawing forming a part of the specification, and in which:

Figure 1 is a front elevational view of the 10 chronoscope of this invention and showing the dial and pointer;

Figure 2 is a longitudinal sectional view 15 through the chronoscope of this invention and showing the interior construction and with the electrical circuit being shown diagrammatically;

Figure 3 is a transverse sectional view of a portion of the chronoscope taken on line 3—3 of Figure 2; and

Figure 4 is a detail elevational view of one of 20 the ratchet wheels.

Referring to the drawing, the numeral 1 refers generally to a case made of plastic or other suitable material and having a base member 2, front wall 3, rear wall 4, and a combined side and 25 top wall 5 arched over the top of the case. The case is provided with a reinforcing bar 6 at the top interconnecting the front and rear walls 3 and 4, respectively. The base, front, and rear walls and top bar 6 may be molded as a unit and the combined side and top member 5 is preferably 30 removably attached in any suitable manner so that access can be had to the interior of the chronoscope for repair or otherwise. The front wall 3 and the rear wall 4 are provided with 35 bearings 7 and 8, respectively, the bearing 7 receiving a hollow, rotatable shaft 9 and the bearing 8 receiving a solid, rotatable shaft 10, as clearly shown in Figure 2. Also, as shown in Figure 2, the shaft 10 extends coaxially through hollow 40 shaft 9 and has suitably affixed thereto at its forward end the pointer 11. The hollow shaft 9 has suitably affixed thereto at its forward end the dial 12. From this construction, it is apparent 45 that the hollow shaft 9 with its dial 12, and the solid shaft 10 with its pointer 11 are independently freely mounted for rotation in the case 1.

As shown in Figure 1, the dial 12 is provided with thirty subdivisions and with ten main divisions, each bearing indicia reading in thousandths of a second. It is further to be noted that the total scale of the dial illustrated represents two hundred and fifty (250) thousandths of a second or $\frac{1}{4}$ of a second. The design of the chronoscope is such that the pointer 11 is driven step-by-step in a clockwise direction, as viewed

in Figure 1, while the dial 12 is alternately rotated step-by-step in a counterclockwise direction. Furthermore, the design is such that the increment of rotation of either the pointer or dial is equal to $\frac{1}{2}$ of the smallest subdivision illustrated in Figure 1, and since there are thirty subdivisions around the dial, sixty strokes are required before the pointer reaches the two hundred and fifty (250) thousandths mark on the dial. Thus in operation, the pointer moves $\frac{1}{2}$ division clockwise, then the dial moves $\frac{1}{2}$ division counterclockwise, then the pointer moves another $\frac{1}{2}$ division clockwise, and so on, so that after thirty strokes of the pointer and thirty strokes of the dial, or sixty strokes in all, the pointer 11 will be pointing downwardly diametrically opposite from the position shown in Figure 1 and at that moment the "250" mark on the dial will coincide with the pointer in that position. The timing of the device is such that this will take place in $\frac{1}{4}$ of a second.

The driving and synchronizing mechanism will now be described. The hollow shaft 9 has suitably fixed thereto for rotation therewith a ratchet wheel 13, as shown in Figure 2, and similarly, the shaft 10 has suitably fixed thereto for rotation therewith the ratchet 14, coaxially positioned relative ratchet wheel 13. Each of the ratchet wheels 13 and 14 is provided with a predetermined number of teeth uniformly spaced and accurately machined around the periphery of the wheel. Figure 4 illustrates ratchet wheel 13 with sixty teeth, spaced 6° apart, around the periphery of the wheel. This is the proper number of teeth required for each of the wheels 13 and 14 for use with the $\frac{1}{4}$ second scale shown in Figure 1 when a 60-cycle source of current is used, as described hereinafter. In Figures 2 and 3, for purposes of clarity only, the pawls 26 and 27 are shown enlarged and the ratchet wheels 13 and 14 are shown with fewer than sixty teeth to clearly show the interaction of the parts. In actual construction, sixty teeth would be used.

The mechanism for driving the ratchet wheels 13 and 14 constitutes the alternating current circuit denoted generally by numeral 15 and shown diagrammatically in Figure 2, and including a conventional plug 16, a make switch 17, a break switch 18, and a solenoid 19 housed within the case 1. Lamp 20 may be included in the circuit, if desired, to provide for a visual stimulus to indicate when the circuit is closed. The solenoid 19 forms part of an electromagnetic device including a fixed iron core 19' extending through the solenoid and an oscillatable armature 21, clearly shown in Figure 3. The base 2 of the case has fixed thereto by suitable means such as the screws 22 a leaf spring 23 upstanding from the base. This leaf spring 23 has fixed thereto intermediate its length the armature 21, which receives oscillations from the solenoid 19 in synchronism with the alternating current oscillations in the electrical circuit 15. Thus, if the plug 16 is plugged into a 60-cycle alternating current circuit, the armature 21 will be attracted towards the iron core 19' at each alternating current peak and will be released under the spring action of the leaf spring 23 each time the alternating current passes from positive to negative and vice versa, and thus for each cycle of the alternating current, there will be two complete cycles of the armature 21. Thus since there are sixty cycles of current impulses per second, there will be one hundred and twenty complete vibrations applied to the armature 21

and the leaf spring 23, or two hundred and forty strokes in both directions.

At the upper free end of leaf spring 23, there is fixed by welding, or other suitable means, a pair of sleeve-like housings 24 and 25, the housing 24 slidably receiving pawl 26 and the housing 25 slidably receiving pawl 27, as shown in Figure 3. The pawls 26 and 27 are normally urged upwardly by the coil springs 28 and 29 positioned beneath the respective pawls within the respective housings. As shown in Figures 2 and 3, pawl 26 is adapted to engage ratchet wheel 14, and pawl 27 is adapted to engage ratchet wheel 13, and preferably the contacting forward face of each of the pawls is flattened where it contacts the ratchet teeth to provide for a substantial engaging surface. The housings 24 and 25 are illustrated as being fixed, one on each side of the leaf spring 23, but it is within the purview of this invention to fix both housings on the same side of the leaf spring, if desired.

As can be seen in Figure 3, when the armature 21 and spring 23 are attracted by the solenoid 19 and moved to the right, the pawl 27 will drive ratchet wheel 13 counterclockwise one increment, that is, the distance equal to the spacing between two adjacent ratchet teeth. This in turn will drive dial 12 counterclockwise $\frac{1}{2}$ of the smallest subdivision shown in Figure 1, or 6° . Then when the solenoid 19 is deenergized, the spring 23 will be released towards the left and the pawl 26 will drive ratchet wheel 14 clockwise, which in turn will drive the pointer 11 $\frac{1}{2}$ of the smallest subdivision illustrated in Figure 1, or 6° , in a clockwise direction. Thus it can be seen that on each stroke of leaf spring 23 to or from solenoid 19, one of the ratchet wheels will be driven an increment of 6° , and since there are two hundred and forty strokes per second of the armature 21 and spring 23, or thirty strokes in each direction per $\frac{1}{4}$ second, the dial and pointer will each move 180° in opposite directions or a total of 360° in $\frac{1}{4}$ of a second. Thus, it can be seen that a chronoscope has been provided in synchronism with an alternating current source in which there is provided a dial and pointer, both of which are adapted to move in opposite directions at 6° intervals in synchronism with the alternating current oscillations.

Although the dial illustrated and the chronoscope described is adapted for readings up to $\frac{1}{4}$ of a second, it is within the purview of this invention to utilize chronoscopes having greater or lesser capacities, as for example, $\frac{1}{8}$ of a second or $\frac{1}{2}$ of a second or other capacities. For example, if the capacity of the chronoscope is to be $\frac{1}{2}$ of a second it would merely be necessary to design the chronoscope so that each increment of movement would be 3° instead of 6° , thus, requiring twice as long for the pointer 11 to reach the end of the scale. To obtain a 3° increment, it is merely necessary to utilize one hundred and twenty ratchet teeth on each of the ratchet wheels 13 and 14 instead of sixty. Also in the $\frac{1}{2}$ second chronoscope, it would be necessary to shorten the length of the stroke of the spring 23 and armature 21, which can be accomplished in a manner well known in the electrical art.

It is further within the purview of this invention to utilize a current source other than the 60-cycle current, if desired. Thus for example, if a 120-cycle current source is used, there would have to be one hundred and twenty teeth in each ratchet wheel to maintain the $\frac{1}{4}$ second scale.

In such embodiment, the pointer and dial would each move sixty times to complete the scale.

The upper surfaces of the pawls 26 and 27 are beveled so that when pawl 26 is driving ratchet wheel 14, the pawl 27 will ride freely in a backward direction without affecting pawl 13, and vice versa. In order to prevent the ratchet wheels 13 and 14 from moving in a backward direction, stationary pawls 30 and 31 are fixed to the bar 6 for engaging the ratchets 13 and 14, respectively, to prevent their backward motion. These pawls 30 and 31 will not interfere with forward counterclockwise motion of ratchet wheel 13 and forward clockwise motion of ratchet wheel 14.

In order to enable the manual return of the dial 12 and pointer 11 to initial zero position, shown in Figure 1, after the chronoscope has been used, the rear end of shaft 10 is knurled as at 32 for manual turning of the shaft 10 and the pointer 11 in a forward direction until the pointer 11 points directly upwardly. Similarly the crystal bezel 33, threaded as at 34 or otherwise affixed to the dial 12, is provided with a knurled periphery 35 so that the dial 12 may likewise be manually rotated forwardly to its zero position, shown in Figure 1. Also, the knurling 32 and 35 provide a ready means whereby the zero setting may be adjusted when the pointer 11 does not fall exactly on the "250" mark.

In operation of the chronoscope, the stroke of leaf spring 23 is adjusted so that each pawl will move a distance greater than the distance between two adjacent teeth but less than the distance between two alternate teeth. This adjustment will insure that the ratchet wheel will be driven the proper increment on each stroke, the increment being the length of a tooth or 6° in the particular chronoscope illustrated. Though the movement of the pawl will probably be somewhat greater than 6°, this extra movement will be taken up by lost motion between the pawl and the ratchet wheel. Before using the chronoscope, it is necessary to set the pointer and dial at zero with one of the pawls in position for driving its ratchet wheel.

In using the chronoscope as a reaction indicator, as for example, when determining the reaction time of an individual in applying the brakes of an automobile, the make switch 17 can be closed to close the circuit 15 and start the pointer 11 and dial 12 in motion. Simultaneously the lamp 20 will light giving an immediate signal to an individual that the operation has commenced. The individual will then withdraw his foot from the accelerator and apply the brakes as fast as he can. As soon as the brake is applied, the break switch 18 will open the circuit 15 and stop motion of pointer 11 and dial 12. At this moment, the pointer and dial will register the reaction time of the particular individual from the time the lamp 20 was energized until the brakes were applied. This chronoscope can also be used for other purposes wherein short intervals of time are to be measured.

Though the hollow shaft 9 is shown mounting the dial 12 and the solid shaft 10 is shown mounting the pointer 11, the shafts may be reversed within the scope of this invention with the hollow shaft mounting the pointer and the solid shaft mounting the dial. In this construction, the dial could be positioned in front of the pointer and be transparent for viewing the pointer.

While the invention has been described in more or less detail, it is not to be limited there-

by, as changes may be made in the form, arrangement and construction of parts, and equivalents may be substituted, without departing from the spirit and scope of the invention as 5 claimed, the forms hereinbefore described being merely preferred embodiments thereof.

I claim:

1. A device for measuring short intervals of time comprising a dial, a pointer associated with said dial, means for converting electrical impulses to mechanical strokes, and means for utilizing said mechanical strokes to impart step-by-step rotation to said dial and pointer, respectively, in opposite directions.
2. A device for measuring short intervals of time comprising a dial, a pointer associated with said dial, means for converting electrical impulses to mechanical strokes, and means for utilizing said mechanical strokes to impart step-by-step rotation to said dial and pointer, respectively, in opposite directions, said first-mentioned means comprising a solenoid, a spring-mounted armature, and a pair of pawls.
3. A device for measuring short intervals of time comprising a dial; a pointer associated with said dial; means for converting electrical impulses to mechanical strokes; and means for utilizing said mechanical strokes to impart step-by-step rotation to said dial and pointer, respectively, in opposite directions; said first-mentioned means comprising a solenoid, a spring mounted armature, and a pair of pawls; said second-mentioned means comprising a ratchet for operating said pointer and another ratchet for operating said dial; and each of said pawls being constructed and arranged to drive one of said ratchets.
4. A chronoscope comprising a dial, a pointer associated with said dial, a pair of shafts for mounting said dial and pointer, respectively, for rotation, and means for rotating said shafts in opposite directions in timed synchronism, one of said shafts being hollow and the other of said shafts extending coaxially through said hollow shaft.
5. A chronoscope comprising a dial, a pointer associated with said dial, a pair of shafts for mounting said dial and pointer, respectively, for rotation, and means for rotating said shafts in opposite directions in timed synchronism, one of said shafts being hollow and the other of said shafts extending coaxially through said hollow shaft, and said means comprising a ratchet wheel fixed to each of said shafts and a pawl for driving each ratchet wheel step-by-step.
6. A chronoscope comprising a dial, a pointer associated with said dial, a pair of shafts for mounting said dial and pointer, respectively, for rotation, and means for rotating said shafts in opposite directions in timed synchronism, said means comprising pawl and ratchet mechanism for each of said shafts and electromagnetic means for operating said mechanism in synchronism with electrical impulses.
7. A chronoscope comprising a rotatable dial, a rotatable pointer associated with said dial, a ratchet for driving said dial, another ratchet for driving said pointer, a pair of pawls for operating said ratchets in opposite directions, a solenoid, a spring-mounted armature associated with said solenoid, and mountings on said armature for said pawls.
8. A chronoscope comprising a rotatable dial, a rotatable pointer associated with said dial a ratchet for driving said dial, another ratchet for

driving said pointer, a pair of pawls for operating said ratchets in opposite directions, a solenoid, a spring-mounted armature associated with said solenoid, and a mounting on said armature for said pawls, said mounting providing spring means for yieldingly urging said pawls against said ratchets.

9. A chronoscope comprising a rotatable dial, a rotatable pointer associated with said dial, means for driving said dial and pointer, respectively, 10 step-by-step in opposite directions, and electromagnetic means for operating said first-mentioned means in synchronism with a source of alternating current.

10. A chronoscope comprising a rotatable dial, 15 a rotatable pointer associated with said dial, means for driving said dial and pointer, respectively, step-by-step in opposite directions, and electromagnetic means for operating said first-mentioned means in synchronism with a source 20 of alternating current, said electromagnetic means including an armature formed of a leaf spring having one end fixed and the other end free, and said first-mentioned means comprising pawl mechanism mounted on the free end 25 of said leaf spring.

11. A device for measuring short intervals of time comprising a rotatable dial, a rotatable pointer associated with said dial, means for alternately rotating said dial and pointer, respectively, 30 step-by-step in opposite directions, and means adapted to facilitate manual return of the dial and pointer to zero setting after operation.

12. A device for measuring short intervals of time comprising a rotatable dial, a rotatable 35 pointer associated with said dial, means for rotating said dial and pointer, respectively, step-by-step in opposite directions, and means adapted to adjust the zero setting of said dial and pointer, respectively.

13. A device for measuring short intervals of

time comprising a rotatable dial, a pointer associated with said dial, and a pair of shafts for mounting said dial and pointer, respectively, for rotation in opposite directions, said dial having 5 a knurled periphery accessible for manual setting of said dial relative said pointer.

14. A reaction time indicator comprising an alternating current circuit, a solenoid in said circuit, make and break switch means in said circuit for closing and opening said circuit to determine the reaction time, an armature associated with said solenoid and adapted to oscillate in synchronism with the current oscillations in said circuit, a leaf spring mounting said armature and adapted to oscillate therewith, said leaf spring having one end fixed and the other end free, pawl mechanism mounted on the free end of said spring for movement therewith, ratchet means intermittently driven by said pawl mechanism, and dial and pointer means alternately operated in opposite directions by said ratchet means for indicating extent of movement of said ratchet means as a measure of the reaction time.
